UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed March 28, 1918, Serial No. 225,342. Renewed April 14, 1922. Serial No. 552,593.

To all whom it may concern:

Be it known that I, Morris P. Holmes, a citizen of the United States, residing at Claremont, in the county of Sullivan and State of New Hampshire, have invented certain new and useful Improvements in Mining Machines, of which the following is a full, clear, and exact specification.

This invention relates to feeding mechanisms for mining machines of the continuous cutter type, which are fed along the face in which the cut is made, and which are moved into and out of cutting position under their own power such feeding mechanism usually having provision for varying the feeding speed and also including a friction device or yielding element, adapted to yield under conditions of overload to prevent breakage, together with means whereby said friction device or element may be loaded to provide a variable resistance to yielding opposed thereby, it being desirable during slow feed to have the friction relatively lightly loaded and more heavily loaded when the mechanism is adjusted to produce a relatively fast feed.

The invention has for one object the provision of improved friction loading mechanism which may be operated to apply the desired force or pressure by a minimum physical effort on the part of the operator; which is of such a character as to maintain itself in maximum loading position when moved into such position; and which is also operable to diminish the friction or to eliminate the same altogether, thereby rendering the friction device inoperative to transmit power, and suspending the operation of the feeding mechanism. A further object of the invention is to provide improved means of the character set forth for controlling the feeding speed, said means likewise having provision for preventing operation of the friction loading means in such manner as to impose a heavy load on the friction when the mechanism is adjusted for slow feed, and said friction loading means having provision for locking said speed controlling means against movement from the slow feed position to the fast feed position except when the friction is completely unloaded, thereby preventing unnecessary

wear on the clutches for controlling the feeding speed.

The foregoing and other objects of the invention, together with means whereby the same may be carried into effect, will best be understood from the following description of one form or embodiment thereof shown for purposes of illustration in the accompanying drawings.

In said drawings,—

Fig. 1 is a plan view, partly broken away, of the complete machine.

Fig. 2 is a fragmentary plan view of the controlling devices.

Fig. 3 is a similar view showing the controlling devices in another position.

Fig. 4 is an irregular transverse vertical section, taken substantially on the line 4—4, Fig. 1.

Fig. 5 is a view similar to Figs. 2 and 3, showing the controlling devices in still another position.

Fig. 6 is a vertical section substantially on the line 6—6, Fig. 1.

The invention is herein illustrated as embodied in a mining machine of the familiar room and pillar type, said machine, as is usual in machines of this type, comprising a body from the forward end of which projects a fixed cutter bar 10 carrying a cutter chain 11 provided with cutter bits 12. The machine body comprises a motor casing 13 and a gear or transmission casing 14, said casing 14, together with suitable framework 15 therein, providing the necessary bearings, guides, and supports for the various parts of the feeding mechanism, except as hereinafter pointed out. Within the motor casing 13 is an electric or other motor 16 of the usual reversible type which operates, through transmission mechanism hereinafter described, to actuate the cutter chain and the feeding means for the apparatus, said feeding means including a feed chain 17 secured at its ends to suitable jacks or other securing devices (not shown) at opposite ends of the path of travel of the machine, said chain passing over a guide roller or sprocket 18 at the rear of the machine, a feed sprocket 19 within the casing 14, and guide rollers or sprockets 20 and 21 at the side of the machine adjacent the rear and front

ends thereof, respectively. The parts thus far referred to, as to their general organization, arrangement, and function, are well known in the art and, except as hereinafter pointed out, require no further description in detail.

The shaft 22 of the motor 16 has fast thereon a beveled gear 23 which meshes with a beveled gear 24 fast on a vertical shaft 25 suitably journaled in the framework. Fast on the shaft 25 is a pinion 26 which meshes with a gear 27 keyed or otherwise secured to a second shaft 28 suitably journaled in the framework. The gear 27 is formed with a hub 29 on which is mounted a sprocket 30 for driving the cutter chain 11, said sprocket being adapted to be clutched to said hub by means of a suitable clutch mechanism indicated by the numeral 31. Such clutch mechanism, being usual in machines of this type, is not illustrated in detail herein.

Loosely mounted on the shaft 28 is a clutch member 32 having an internal clutch face engaged by friction clutch members or shoes 33 connected by toggle links 34 with a clutch operating member 35 having a splined connection with the shaft 28. Movement of the member 35 toward the member 32 causes the toggle links 34 to force the shoes outwardly against the clutch face of the member 32, thereby frictionally connecting said member to the shaft 28. The member 35 is normally pressed toward the clutch member 32 by means of a spring 36 bearing at one end against an interior shoulder on the member 35 and at its opposite end against a nut 37 on the threaded end of the shaft 28, whereby the tension of said spring may be adjusted. In the operation of the friction device last described, the member 32 is caused normally to rotate with the shaft 28 and thus transmit the feed, but is permitted to yield or slip on said shaft should an unusual resistance be encountered. The resistance opposed by said device against such yielding or slipping is determined by the force with which the member 35 is pressed toward the member 32 by the spring 36 or by said spring supplemented by other means hereinafter referred to.

The hub of the member 32 is formed with a pinion 38 which meshes with a gear 39 rotatably mounted on a fixed vertical shaft 40 suitably supported by the framework. Slidably and rotatably mounted on the shaft 40 is a sleeve 41 having at its end a clutch face 42 adapted to engage a cooperating clutch face on the gear 39. The sleeve 41 is formed with a toothed portion constituting a pinion 43 which meshes with a gear 44 fast on the hub of the feed sprocket 19, which sprocket is rotatably mounted on an upright shaft 45 suitably fixed in the framework.

By the connections above described the feed sprocket 19 is rotated to produce a rel-

atively fast feed. In order to provide for a relatively slower feeding speed, the following transmission mechanism, operative alternatively with a portion of the mechanism last described, is provided:

The hub 47 of the gear 39 is formed with a pinion portion 48 which meshes with a gear 49 rotatably mounted on a stud shaft 50 suitably supported in the machine frame. The gear 49 has a pinion portion 51 which meshes with a gear 52 fast on a sleeve 54 rotatably mounted on an upright shaft 53 also fixed in the machine frame. The sleeve 54 has fast thereon a pinion 55 which meshes with a gear 56 rotatably mounted on the shaft 40.

The sleeve 41 is provided on its end opposite the clutch face 42 with a second clutch face 57 adapted to engage a cooperating clutch face on the gear 56. By moving the sleeve 41 longitudinally to cause one or the other of the clutch faces 42 or 57 to engage the cooperating clutch face on the gear 39 or the gear 56, the pinion 43 on said sleeve, which pinion drives the feed sprocket 19 through the gear 44, may be rotated either at fast speed directly by the gear 39 or at slow speed from said gear 39 through the gearing 48, 49, 51, 52, 55, and 56.

In order that said clutch sleeve 41 may be conveniently shifted, said sleeve is formed with a circumferential groove which is engaged by a clutch fork 58 formed on a lever 59 pivoted at 60 to the framework. The lever 59 is provided with a slot which receives in a well known manner an eccentric pin or stud 61 on the end of a shaft 62 journaled in the framework and provided at its opposite end with a beveled gear 63 which meshes with a gear segment 64 on a hand lever 65 rotatably mounted on a stud 66 projecting from the framework. By turning the lever 65 into the position shown in Fig. 1, the clutch fork 58 is operated to engage the clutch face 42 on the sleeve 41 with the gear 39, thereby connecting the parts to produce the fast feed. By moving the lever 65 into the position shown in Figs. 3 and 5, the clutch fork 58 is moved to engage the clutch face 57 with the gear 56, thereby connecting the parts to produce the slow feed. By moving the lever 65 into the neutral position shown in Fig. 2, the clutch faces 42 and 57 will both be disengaged from their cooperating clutch faces on the gears 39 and 56, causing the feed sprocket to remain idle.

For the purpose of supplementing the action of the spring 36 when it is desired to more heavily load the friction, i. e. when it is desired to force the members 33 into tighter engagement with the inner periphery of the member 32, and also for the purpose of preventing the spring 36 from forcing these parts into engagement when this is desirable, the following mechanism is provided.

Rotatably mounted on the clutch operating member 35, is a trunnion ring 67 cooperating with the bifurcated end of a lever 68 pivoted at its opposite end to an upright 5 69 supported by the framework. Intermediate its ends the lever 68 is provided with a slot which receives an eccentric pin 70 on the end of a shaft 72 journaled in the framework and provided at its opposite end with 10 a beveled gear 73 meshing with a gear segment 74 fixed to the hub 75 of a controlling member or lever 76, said hub being suitably journaled in the framework. With the levers 68 and 76 in the neutral or normal position shown in Figs. 2, 3, and 4, the friction is loaded only by the spring 36 exerting its normal pressure, determined by the adjustment of the nut 37, upon the member 35. When the lever 76 is in the position shown 15 in Fig. 1, the lever 68 is caused to press downwardly upon the ring 67, thereby supplementing the action of the spring 36, and causing the shoes 33 to engage the clutch surface on the member 32 with an increased 20 pressure. When the lever 76 is moved into the position shown in Fig. 5, the lever 68 is caused to lift upwardly on the ring 67, thereby overcoming the tension of the spring 36, rendering the friction device inoperative 25 to transmit power from the shaft 28 to the clutch member 32 and pinion 38, causing the feed sprocket to remain idle, and suspending the operation of the feeding mechanism. It will now be observed that the spring 36 and the lever 68 and its associated parts 30 both cooperate with the member 35 and together go to make up friction loading mechanism which is adapted to completely unload, to lightly load, and to heavily load the friction. It will also be noted that by adjustment of the member 37 the light loading limit may be varied, while by adjustment either of the member 69 or of the member 40 45 81 the maximum loading limit may be changed.

Pivoted intermediate its length to the outer end of the lever 76, is a lever or handle 77 having at its outer end a suitable handle grip 78 and at its opposite end a projection 79 preferably provided with a roller. The projection or roller 79 cooperates with a slot 80 in a keeper or bracket 81 preferably adjustably secured to the framework by means of screws 82 passing through an elongated opening or slot in said bracket. The levers 76 and 77 together with the slotted member 81 make-up a toggle mechanism for operating the controlling member or lever 76, providing an increased leverage whereby said last mentioned lever may be operated to apply the desired force or pressure to the friction device by a minimum of physical effort on the part of the operator. When the lever 77 is turned about its pivot in a counter-clockwise direction from the normal or neu-

tral position shown in Fig. 3 into the position shown in Fig. 1, the projection 79, which engages the fixed abutment furnished by the wall of the slot 80, exerts a cam or wedging action upon the lever 77, moving 70 the latter bodily and carrying with it the lever 76, thereby forcing the latter lever into its friction loading position. The slot 80 is preferably disposed substantially perpendicular to the length of the lever 77 when 75 the latter is in the position shown in Fig. 1, so that the thrust of said lever is normal to the abutment formed by the side of said slot, this action serving to retain the parts in adjusted position. If desired, the lever 77 may be turned in a counterclockwise direction slightly beyond the position shown in Fig. 1, causing the projection 79 to be forced, by the reaction of the spring 36 transmitted through the lever 76, against the outer end 80 of the slot 80, whereby said reaction serves more securely to retain the parts in the friction loading position.

By turning the lever 77 in a clockwise direction, from the position shown in Fig. 3 90 into that shown in Fig. 5, about the axis of the projection 79, the lever 76 is moved in the opposite direction from its neutral position, causing the friction device to be wholly unloaded and so rendered inoperative as 95 above explained. The movement of the parts in the manner last described is preferably limited by a fixed stop 83 projecting from the framework and engaged by the lever 76 100.

When the feed controlling lever 65 is in the slow feed position shown in Fig. 3, the end of said lever, by engagement with the lever 76, locks the latter lever against movement in the direction to load the friction. Said lever 76 is formed with a lug or projection 84 which, when the lever 65 is in the slow feed position, engages said lever 65 105 and locks the same in said position until the controlling member or lever 76 is moved into the position shown in Fig. 5, thereby 110 making it impossible to change the feeding speed without first completely releasing the friction.

The complete operation may be briefly reviewed as follows: As shown in Fig. 3, the mechanism is adjusted to provide a slow feed with a relatively light load on the friction. In this position the lever 65 is locked against movement by the lug 84, 115 while the lever 76 is held against movement in the direction to further load the friction by said lever 65. By operating the handle 78 to turn the lever 77 into the position shown in Fig. 5, the friction is rendered inoperative and the lever 65 released, permitting the same to be turned in a counter-clockwise direction. The lever 65 may thereupon be turned into the neutral position shown in Fig. 2, which is the position to suspend operation of the feeding mechanism. The re-

action of the spring 36 causes the levers 76 and 77 to be returned to their normal position, as shown in Fig. 2, when the handle 78 is released. Further movement of the lever 65 from the neutral position shown in Fig. 2 to the position shown in Fig. 1 causes the mechanism to be adjusted for the fast feed. Thereafter the lever 77 may be moved into the position shown in Fig. 1, thereby loading the friction to the maximum degree, said lever being automatically retained in this position until intentionally released therefrom. It will be observed that the feeding movement of the machine can be arrested or suspended at any time, either by the movement of the lever 65 into the neutral position shown in Fig. 2, or by movement of the lever 77 into the friction releasing position shown in Fig. 5, according to convenience.

It will also be noted that in my improved construction movement of the parts to apply the maximum load to the clutch is facilitated and that the parts are automatically held in the desired position and more particularly in maximum loading position in such manner as despite the vibration of the machine to free the operator for other work. It will also be observed that the slot 80 in the keeper 81 serves to control and limit the movement of the lever 77, and consequently of the lever 76, thereby limiting the extent to which the friction device may be loaded, and preventing injurious or dangerous overloading of the same, as is possible in machines in which the load imposed upon the friction is determined solely by the muscular effort exerted by the runner. Attention is also directed to the fact that my improved construction is also adapted to use in connection with interlocking connections and more particularly interlocking control levers between the friction mechanism and the variable speed mechanism, my improved construction being adapted to be applied to the friction lever of such a mechanism without in any way interfering with the interlocking function, and when so applied operating to hold those connections or levers in interlocked relation or release the same therefrom. Here it will be noted that I do not claim broadly the interlocking of the friction and speed controlling levers, this being claimed in my copending application, Ren. Ser. No. 555,916, filed Apr. 21, 1922. It will be observed that my improved mechanism includes means for automatically maintaining different loading limits for the clutch when the different trains of gearing are in operation. Observing Fig. 3, it will be seen that when the slow speed train is in operation the loading limit for the clutch is the pressure which is exerted upon the member 35 by the spring 36. When the parts are in the position of Fig. 1, the loading

limit is the pressure exerted at that time by the spring 36 and by the levers 76, 68 and related parts. In both cases, whether the fast train or the slow train is in use there is a definite loading limit for the clutch and by this term I mean that the load which is imposed upon the clutch to force its component clutch elements into engagement is definitely limited. It will therefore be understood that where I refer in the claims to a "loading limit for the clutch" I mean a limit to the pressure or force which may act to force the parts of the clutch into engagement with each other.

While I have in this application specifically described one embodiment, which my invention may assume in practice, it will be understood that this form of the same is used for purposes of illustration, and that the invention may be modified and embodied in various other forms without departing from its spirit or the scope of the appended claims.

What I claim as new and desire to secure by Letters Patent is:

1. The combination with a mining machine, of feeding means therefor including a yielding mechanism, a controlling member for said mechanism operatively connected thereto, and means including a grasping handle for said controlling member carried thereby and movable with said member and relative thereto for facilitating the loading of said mechanism by multiplying the pressure exerted on said handle by an operator.

2. The combination with a mining machine, of feeding means therefor including a yielding mechanism, a controlling member for said mechanism operatively connected thereto, and means including a handle for said controlling member movable with said member and relative thereto for limiting the loading of said mechanism which can be effected by an operator.

3. The combination with a mining machine, of feeding means therefor including a yielding mechanism, a controlling member for said mechanism operatively connected thereto, and cam means including a handle for said controlling member movable with said member and relative thereto for limiting the loading of said mechanism by an operator.

4. The combination with a mining machine, of feeding means therefor including a yielding mechanism, a controlling member for said mechanism operatively connected thereto, and cam means including a handle for said controlling member movable with said member and relative thereto for limiting the loading of said mechanism and holding said handle in loaded position.

5. The combination with a mining machine, of feeding means therefor including a yielding mechanism, a controlling mem-

ber for said mechanism operatively connected thereto, and means including an operating handle for said controlling member movable with said member and relatively thereto for successively unloading and limiting the loading of said yielding mechanism by an operator.

6. The combination with a mining machine, of feeding means therefor including a yielding mechanism, a controlling member for said mechanism operatively connected thereto, and means including a handle pivoted to said controlling member and a cooperating member engageable by said handle for successively facilitating and limiting the loading of said mechanism by an operator.

7. The combination with a mining machine, of feeding means therefor including a yielding mechanism, a controlling member for said mechanism operatively connected thereto, and controlling means for said member including a handle pivoted to said controlling member and having a cam engaging portion on the opposite side of its pivot from said handle, and a cooperating cam member engageable by said portion.

8. The combination with a mining machine, of feeding means therefor including a yielding mechanism, a controlling member for said mechanism operatively connected thereto, and controlling means for said member including a handle pivoted to said controlling member and having a cam engaging portion on the opposite side of its pivot from said handle, and means forming a cam slot in which said portion moves.

9. The combination with a mining machine, of feeding means therefor including a yielding mechanism, a controlling member for said mechanism operatively connected thereto, and controlling means for said member including a handle pivoted to said controlling member and having a cam engaging portion on the opposite side of its pivot from said handle, and means forming a cam slot in which said portion moves, said last mentioned means being adjustable in a direction transverse to said pivot.

10. In a mining machine, feeding mechanism including a friction mechanism, a controlling member for said mechanism operatively connected thereto, and cooperating cam means including an operating handle pivoted on said friction controlling member for increasing the range of possible movement of said member by an operator and holding it in maximum loaded position.

11. In a mining machine, feeding mechanism including a friction mechanism, a controlling member for said mechanism operatively connected thereto, and cooperating cam means including a toggle connected operating handle pivoted on said friction controlling member for increasing the range of

possible movement of said member by an operator and holding it in maximum loaded position.

12. In a mining machine, feeding mechanism including a friction mechanism, a controlling member for said mechanism operatively connected thereto, and cooperating cam means including an operating handle pivoted on said friction controlling member for increasing the range of possible movement of said member by an operator and holding it in maximum loaded position, a portion of said cam means being adjustable.

13. The combination with a mining machine, of feeding means therefor including a variable speed mechanism and a yielding mechanism, interlocking levers for said mechanisms operatively connected thereto and operative in one position to prevent manual loading of said yielding mechanism, and means for positively limiting the loading of said yielding mechanism when said levers are disengaged including supplemental pivoted lever mechanism.

14. The combination with a mining machine, of feeding means therefor including a variable speed mechanism and a yielding mechanism, interlocking levers for said mechanisms operatively connected thereto and operative in one position to prevent manual loading of said yielding mechanism, and means for facilitating and positively limiting the loading of said yielding mechanism when said levers are disengaged including supplemental pivoted lever mechanism.

15. The combination with a mining machine, of feeding means therefor including a variable speed mechanism and a yielding mechanism, interlocking controlling members for said mechanisms operatively connected thereto operative in one position to prevent manual loading of said yielding mechanism, and means including an operating handle for and carried by one of said members for positively limiting the loading of said yielding mechanism when said members are disengaged.

16. The combination with a mining machine, of feeding means therefor including a variable speed mechanism and a yielding mechanism, interlocking controlling members for said mechanisms, and means including a toggle connected operating handle for one of said members for facilitating the loading of said yielding mechanism when said members are unlocked.

17. The combination with a mining machine, of feeding means therefor including a variable speed mechanism and a yielding mechanism, interlocking controlling members for said mechanisms, and means including a pivoted handle on one of said members for successively facilitating and

limiting the loading of said yielding mechanism when said members are unlocked.

18. In a mining machine, the combination with feeding mechanism including a yielding element, of means for supplementing the normal resistance to yielding opposed by said element, and means for rendering said first named means operative or inoperative, said last named means including an angularly and bodily movable lever and means engaged by said lever for holding the same against bodily movement when in an angular position corresponding to the operative position of said first named means.

19. In a mining machine, the combination with feeding mechanism including a yielding element, of means for supplementing the normal resistance to yielding opposed by said element, and means for rendering said first named means operative or inoperative, said last named means including an angularly and bodily movable lever and an abutment having a face engaged by said lever, said face being substantially perpendicular to the length of said lever when the latter is in an angular position corresponding to the operative position of said first named means.

20. In a mining machine, the combination with feeding mechanism including a yielding element, of means for supplementing the normal resistance to yielding opposed by said element, and means for rendering said first named means operative or inoperative, said last named means including an angularly and bodily movable lever, a keeper having a slot, and means on said lever engaging said slot for controlling the movements of said lever.

21. In a mining machine, the combination with feeding mechanism including a yielding element, of means for increasing the resistance to yielding opposed by said element, and means for rendering said first named means operative or inoperative, said last named means including an angularly and bodily movable lever, an adjustable abutment, and means on said lever engaging said abutment for controlling the movements of said lever.

22. In a mining machine, the combination with feeding mechanism including a yielding element, of means for increasing the resistance to yielding opposed by said element, and means for rendering said first named means operative or inoperative, said last named means including an angularly and bodily movable lever, an adjustable bracket having a slot, and a projection on said lever engaging said slot for controlling the movements of said lever.

23. In a mining machine, the combination with feeding mechanism including a yielding element, of means for increasing the resistance to yielding opposed by said element, a lever for operating said means, a

second lever pivoted to said first named lever for actuating the same, and an abutment engaged by said second lever.

24. In a mining machine, the combination with feeding mechanism including a yielding element, of means for increasing the resistance to yielding opposed by said element, a lever for operating said means, a second lever pivoted to said first named lever for actuating the same, and an abutment engaged by said second lever, said abutment having a face disposed substantially perpendicular to the length of said second lever when the latter is in a position to cause operation of said resistance increasing means.

25. In a mining machine, the combination with feeding mechanism including a yielding element, of means for increasing the resistance to yielding opposed by said element, a lever for operating said means, a second lever pivoted to said first named lever for actuating the same, an adjustable bracket having a slot, said slot being disposed substantially perpendicular to the length of said second lever when the latter is in a position to cause operation of said resistance increasing means, and a projection on said second lever engaging said slot for controlling the movements of said lever.

26. In a mining machine, the combination with feeding mechanism including a yielding element, of means for increasing the resistance to yielding opposed by said element, and toggle mechanism for operating said resistance increasing means.

27. In a mining machine, the combination with feeding mechanism including a yielding element, of means for supplementing the normal resistance to yielding opposed by said element, and toggle mechanism for operating said last named means, said mechanism having provision for retaining the same in operative position.

28. In a mining machine, the combination with feeding mechanism including a yielding element, of means for increasing the resistance to yielding opposed by said element, and means for operating said resistance increasing means including a lever operatively connected therewith, a hand lever pivoted to said first named lever for actuating the same, and a fixed abutment engaged by said hand lever.

29. In a mining machine, the combination with feeding mechanism including a yielding element, of means for increasing the resistance to yielding opposed by said element, and means for operating said resistance increasing means including a lever operatively connected therewith, a second lever pivoted intermediate its ends to said first named lever, a fixed abutment, and means carried by one end of said second lever for engaging said abutment.

30. In a mining machine, the combination with feeding mechanism including a yielding element, of means for increasing the resistance to yielding opposed by said element, and means for rendering said first named means operative or inoperative, said last named means including a lever operatively connected with said first named means, a second lever pivoted intermediate its ends to said first named lever, a fixed keeper having a slot, and means carried by one end of said lever and engaging said slot for controlling the movements of said second lever.
31. In a mining machine, the combination with feeding mechanism including a yielding element, of means for increasing the resistance to yielding opposed by said element, toggle mechanism for operating said resistance increasing means, and means for limiting the movement of said toggle mechanism.
32. In a mining machine, the combination with feeding mechanism including a yielding element, of means for increasing the resistance to yielding opposed by said element, toggle mechanism for operating said resistance increasing means, and a fixed stop engaged by one of the members of said toggle mechanism for limiting the movement thereof.
33. In a mining machine, the combination with feeding mechanism including a yielding element, of means for increasing the resistance to yielding opposed by said element, a lever for operating said means, a fixed stop engaged by said lever for limiting the movement thereof, a second lever pivoted to said first named lever for actuating the same, and an abutment engaged by said second lever.
34. In a mining machine, the combination with feeding mechanism including a friction device, of means for loading said friction device, and toggle mechanism for operating said loading means.
35. In a mining machine, the combination with feeding mechanism having provision for relatively fast and slow speeds and including a yielding element, of a controlling member and connections for controlling the feeding speed, means for increasing the resistance to yielding opposed by said element, toggle mechanism for operating said resistance increasing means, and means carried by a member of said toggle mechanism for locking said controlling member against operation.
36. In a mining machine, the combination with feeding mechanism having provision for relatively fast and slow speeds and including a yielding element, of a controlling member and connections for controlling the feeding speed, means for increasing the resistance to yielding opposed by said element, a lever for operating said last named means, said lever having a shoulder adapted to engage and lock said controlling member, a second lever pivoted to said first named lever for actuating the same, and an abutment engaged by said second lever.
37. In a mining machine, the combination with feeding means and transmission mechanism for actuating said feeding means, said mechanism including a yielding element, of means for increasing the resistance to yielding opposed by said element, and toggle mechanism for operating said resistance increasing means, said toggle mechanism being operable to render said yielding element inoperative to transmit power.
38. In a mining machine, the combination with feeding means and transmission mechanism for actuating said feeding means, said mechanism including a yielding element, of means for rendering said element inoperative to transmit power, an operating lever for controlling said last named means, and a hand lever pivoted to said operating lever for moving the same.
39. In a mining machine, the combination with feeding mechanism including a yielding element, of means for increasing the resistance to yielding opposed by said element or for rendering said element inoperative to transmit power, an operating lever for controlling said last named means, a hand lever pivoted to said controlling lever for moving the same, and a fixed abutment engaged by said hand lever.
40. In a mining machine, the combination with feeding means and transmission mechanism for actuating said feeding means, said mechanism including a yielding element, of means for rendering said element inoperative to transmit power, an operating lever for controlling said last named means, a hand lever pivoted to said operating lever for moving the same, and means for controlling the movement of said hand lever.
41. In a mining machine, the combination with feeding means and transmission mechanism for actuating said feeding means, said mechanism including a yielding element, of means for increasing or diminishing the normal resistance to yielding opposed by said element, an operating lever for controlling said last named means, a hand lever pivoted to said operating lever for moving the same, and means for controlling the movements of said hand lever.
42. In a mining machine, the combination with feeding means and transmission mechanism for actuating said feeding means, said mechanism including a yielding element, of means for rendering said element inoperative to transmit power, an operating lever for controlling said last named means, a hand lever pivoted intermediate its ends to said operating lever, a fixed slotted keeper, and means carried by the end of

said hand lever and engaging the slot in said keeper for controlling the movement of said hand lever.

43. In a mining machine, the combination with feeding mechanism including a yielding element, of means for supplementing the normal resistance to yielding opposed by said element or for rendering said element inoperative to transmit power, an operating lever for controlling said last named means, a hand lever pivoted intermediate its ends to said operating lever, a fixed keeper having a slot, and means on the end of said hand lever and engaging said slot for controlling the movements of said hand lever.

44. In a mining machine, the combination with feeding mechanism having provision for relatively fast and slow feeding speeds and including a yielding element, of means for increasing the resistance to yielding opposed by said element, toggle mechanism for operating said resistance increasing means, and means for controlling the feeding speed and for holding said toggle mechanism against operation to increase said resistance.

45. In a mining machine, the combination with feeding mechanism having provision for fast and slow speeds and including a yielding element, of interlocking controlling members operatively connected to said mechanisms for controlling the speed of said feeding mechanism and the resistance to yielding of said yielding element, and cooperating controlling means including a cam member pivoted on one of said members and forming the operating handle therefor.

46. In a mining machine, the combination with feeding mechanism having provision for fast and slow speeds and including a yielding element, of interlocking controlling members operatively connected to said mechanisms for controlling the speed of said feeding mechanism and the resistance to yielding of said yielding element, and co-

operating controlling means including a cam member pivoted at a point between its ends to one of said members and forming the operating handle therefor.

47. In a mining machine, the combination with feeding mechanism having provision for fast and slow speeds and including a yielding element, of interlocking controlling members operatively connected to said mechanisms for controlling the speed of said feeding mechanism and the resistance to yielding of said yielding element, and cooperating controlling means including a cam member pivoted on the controlling member for said yielding element and forming the operating handle therefor.

48. In a mining machine, the combination with feeding mechanism having provision for fast and slow speeds and including a yielding element, of interlocking controlling members operatively connected to said mechanisms for controlling the speed of said feeding mechanism and the resistance to yielding of said yielding element, and cooperating controlling means including a cam member pivoted at a point between its ends on the controlling member for said yielding element and forming the operating handle therefor.

49. In a mining machine, the combination with feeding mechanism having provision for fast and slow speeds and including a yielding element, of interlocking controlling members operatively connected to said mechanism for controlling the speed of said feeding mechanism and the resistance to yielding of said yielding element, and cooperating cam means including a fixed element and a cooperating movable element pivoted to the controlling member for said yielding element and forming the operating handle therefor.

In testimony whereof I fix my signature.

MORRIS P. HOLMES.
